PUMP AND MOTOR HYDRAULIC ACTUATOR

Carl J. Bishopberger, Minneapolis, Minn., assignor
to Minneapolis-Honeywell Regulator Company,
Minneapolis, Minn., a corporation of Delaware

Application November 16, 1949, Serial No. 127,749

10 Claims. (Cl. 60—52)

1

The present invention relates to hydraulic operators and more particularly to improvements in the type of hydraulic operator which includes a pump, motor means for operating the pump and an actuator operated by the pump.

It is an object of this invention to provide in a hydraulic operator of this type a simplified design of parts which permits economy in manufacture and ease in assembly.

It is also an object of this invention to provide in a hydraulic operator a sealed unit in which a single gasket member positively seals the operator.

A further object of this invention is to provide an improved design of a motor of the transformer type.

It is another object of this invention to provide an improved pump design for a hydraulic operator having a simplified valve mechanism.

It is further an object of this invention to provide a simplified check valve for the pump of the hydraulic operator.

It is still further an object of this invention to provide in an hydraulic operator of this type an improved seal for such a unit.

Another object of this invention is to provide a simplified terminal block assembly for the electric motor of the hydraulic operator, the terminal assembly isolating high and low voltage connections thereto.

These and other objects of this invention will become apparent from the reading of the attached specification together with the drawings wherein:

Figure 1 is a side elevation view of the operator;

Figure 2 is another side elevation view of the operator with a portion of the casing in section to show the location and arrangement of parts;

Figure 3 is a plan view of the pump unit of the operator;

Figure 4 is an end elevation view of the pump of Figure 3;

Figure 5 is a side elevation view of the pump of Figure 3 in section on the line 5—5 of Fig. 3;

Figure 6 is a plan view of the electric motor of the operator;

Figure 7 is an end elevation view of the motor of Figure 6;

Figure 8 is a sectional view of the motor terminals; and

Figure 9 is a schematic view of the check valve.

The hydraulic operator of the subject invention, as is shown generally in Figures 1 and 2, is made up of a motorized pump or power unit 10 and the hydraulic actuator unit 11, these units being con-

2

tained in a composite casing structure formed of an upper cylindrical casing member 12 and a lower cylindrical casing member 13. The operator is designed to be normally mounted, by means of a bracket 14 attached to the upper casing member 12, in an upright or vertical position with the upper casing member 12 located above the lower casing member 13. In this normal position, a slideable output shaft 15 projecting through an aperture 19 in the lower casing member 13 is disposed to move vertically up or down. The shaft 15 is connected to an output lever 16 which is pivoted by means of a support member 17 attached to the lower casing member 13. Vertical movement of shaft 15 causes an output link 18 on the end of lever 16 to similarly move up or down in the normal position of the operator, this output link being suitable for attachment to apparatus which the operator is to control, such as a damper.

As will be seen in Figure 2, shaft 15 is guided in its movement by means of a sleeve 20 fitted into the aperture 19 in the lower casing member 13 and secured thereto by suitable means such as crimping. The end of shaft 15 within the casing member 13 is attached by any suitable means (not shown) to a disk like member 21, these members operating in a single unit which may if desired be so machined or manufactured. Disk member 21 and hence shaft 15 are urged upwardly within the lower casing member 13 by means of a compression spring 22 which encircles the sleeve 20 and shaft 15 abutting at one extremity against the lower portion of casing 13 and at the other extremity against the disk member 21.

The disk 21 and shaft 15 form together a plunger or output portion of the hydraulic actuator whose movement in an upward direction, as previously noted, is controlled by means of spring 22, and whose movement in a downward direction is controlled by means of a diaphragm member 23 positioned in abutting relationship with the upper surface of disk 21. Like the casing members 12 and 13 disk member 21 and diaphragm member 23 are cylindrical in form. The diaphragm member is made of a suitable flexible material such as rubber and is so positioned within the casing member 13 that it is concentric therewith and is disposed in contact with a transversely extending flange portion 24 of casing member 13. Diaphragm 23 forms the movable end wall of a chamber which varies in volume, the chamber being completed by a supporting plate 25 also circular formed and disposed at its outer extremity on top of the diaphragm member.

Supporting plate 25 has a dish shape configuration with three raised portions 26 spaced 120 degrees apart, the purpose of which is to form a stop member for the diaphragm and disk and provide for a given volume for chamber capacity in the collapsed position of the diaphragm member 23.

The variable chamber of the actuator unit thus formed by the diaphragm 23 and supporting plate 25 is sealed by the engagement of the diaphragm with the supporting plate, and, in addition, the diaphragm 23 is provided with a beaded or raised portion 27 at its outer extremity which encircles the supporting plate. The supporting plate 25, diaphragm 23 and lower casing member 13 are held in assembled relationship by means of a flanged portion 30 of the upper casing member 12 which flange forms a shoulder as at 31 against which the plate 25 abuts for the purpose of positioning the upper casing member 12 with respect to the actuator unit. Flange 30 is bent or crimped over the flange portion 24 of lower casing member 13, such as by spinning, to hold these parts in the above identified relationship and insure a seal between the diaphragm and support plate 25. The flange 30, which is channel like in cross section, further urges the beaded portion 27 of diaphragm member 23 into engagement with the end of the supporting plate and against the shoulder 31 of casing member 12. In this manner a second seal is insured between the supporting plate 25 and the casing member 12. While the casings 12, 13, the supporting plate 25 and diaphragm 23 are best held in assembled relationship by means of bending over the flange portion 30 of casing member 12, it is to be understood that any other means which clamp the casing members together may be employed.

The variable chamber formed by supporting wall 25 and diaphragm 23 is designed to receive a working fluid or medium 40 which is fed into said chamber through an aperture in the supporting wall (not shown) by means of the pump 41 mounted thereon by any suitable means, such as screws 42. Presence of the working medium or fluid 40 in the variable chamber and under pressure causes the variable chamber to expand forcing the central portion of the diaphragm 23 adjacent to the disk 21 to be moved downward forcing the shaft 15 and disk 21 against the compression force of spring 22 to operate the lever member 16. The working medium 40, which is fed through the aperture in the supporting wall 25 by means of the pump 41, is normally contained in a fixed chamber formed by the upper casing 12 and the supporting wall 25 which is sealed as heretofore noted by means of the flange 30 and beaded portion 27 of diaphragm 23. This chamber above the supporting wall 25 is known as the motorized pump or power unit and is designed to provide the reservoir or sump for the working medium 40, as indicated in Figure 2.

The pump 41, as shown in detail in Figures 3, 4 and 5, comprises a cylindrical piston 44 positioned within the housing 45 having a cylindrical bore to fit the piston. The piston 44 is a solid cylindrical member having two working extremities each of which has a notch 46 or groove therein segmental in shape thereby providing at the extremities of said piston a surface which is segmental in cross section. The grooves 46, as indicated in Figure 5, are located at opposite ends and opposite sides of the piston 44 and serve to cooperate with inlet 47 and outlet 48 passages to the chambers formed within member 45 by piston

44 in a manner to become evident as this disclosure proceeds.

The inlet passages 47 are located on the upper surface of the cylinder member 45 and lead to openings in the top of the pump which are covered by screens 50, the screens being retained on the member 45 by means of spring clips 51. The outlet passages 48 are located in the lower portion of the pump or member 45 and similarly lead to the working chambers of the pump. As shown in Figure 3, these outlet passages 48 are connected by means of grooves 52 to the end of a check valve mechanism indicated generally at 55.

Check valve 55 which is formed within the pump structure 41 consists primarily of a hollow piston member 56 located within a second cylindrical bore 57 in member 45. This cylindrical bore 57 of valve chamber has a pair of passages leading thereto, one passage, indicated at 58 (see Figures 4 and 9), being located in the upper surface of member 45 and venting the valve chamber to the enclosure surrounding the pump. A second passage 60 is located in the bottom of the member 45 and leads to an aperture (not shown) in the supporting plate 25 to provide a passage through the check valve mechanism to the variable chamber of the hydraulic actuator. Piston 56 within the valve chamber or bore 57 controls the opening and closing of passage 58 such that the working medium 40 may flow from the pump through the check valve mechanism to the variable chamber of the actuator when the piston is in one position and from the variable chamber through the check valve to the sump when the piston is in a second position. Piston 56 has a shoulder portion 61 formed midway along its bore, this shoulder portion cooperating with a ball check member 62 which is urged by a spring 63 to be seated on the shoulder portion and thereby forming a ball check valve member 62 within the piston. The ball check member 62 is seated on the shoulder portion 61 by means of a spring 63 under a given spring tension in such a manner that the ball check valve formed thereby will not open until a predetermined pressure is exerted on the surface of the ball member 62. Thus, when the oil or working medium enters valve check mechanism 55 it exerts a pressure against the surface of the ball check in addition to the piston. Depending upon the pressure present in the opposite end of the piston or within the chamber 57, the piston will then move within the bore to cover the port 58 leading to the oil sump and will continue to move until a stop member 65 is engaged at which point the piston will stop. Upon increased pressure being applied to the base of the ball check member 62, this check valve will open providing a passage for the fluid through the hollow portion of the piston, that is, the ball check valve member and to the passage 60 leading to the variable chamber of the actuator unit. In the absence of pressure on the pump side of the check valve member, the ball check will again reseat itself and the piston will move in the opposite direction to open the passage 58 leading to the sump.

The pressure or presence of the working medium in the check valve chamber is obtained through operation of the pump whose piston 44 is designed to reciprocate within the cylindrical bores of member 45 and also oscillate in such a manner that it will alternately cover and uncover the inlet 47 and outlet 48 passages thereto as it moves transversely within the cooperating cylinder member. The oil or working me-

dium 40 which enters the pump through the screened inlet port 47 passes through the respective ends of the pump chambers depending upon which of the inlet ports are open or closed by the respective notched ends of piston 44. When the pump reciprocates and oscillates oil will be forced on through the outlet ports 48 to the check valve chamber and in the manner described above the working medium will be transmitted to the variable chamber of the actuator. The oscillating and reciprocating motion of the piston 44 is obtained by means of a ball type linkage 66 attached to the central portion of piston 44. This ball linkage or joint fits into a bore or hole 69 eccentrically located in a drive cam 67 carried on the extremity of the shaft 68 of a motor 70. Rotation of the cam due to the rotation of the motor will cause the ball member attached to the piston 44 to describe an oscillating and reciprocating motion which motion is transmitted to the piston for operating the valve and driving the piston during intake and pressure strokes.

Motor 70, as shown in Figures 6 and 7, is a four pole motor of the transformer type and is mounted on the pump 41 and hence the supporting plate 25 by means of screws 42 which thread through mounting brackets or flanges 71 formed on the pump caging member 45. The stator 73 of the motor is made up of a plurality of laminations of magnetic material which are held together by a mounting bracket 72, the laminations when assembled forming an O type yoke with four poles 75a, 75b, 75c and 75d thereon. The laminations are provided with notches such that the resultant poles formed thereby have slots thereon in which are positioned shaded coils 74 on short circuited conductors. A pair of primary 76 and secondary 77 windings for stator 73 are positioned on the yoke of the stator with the two primary windings positioned on diametrically opposite sides of the yoke and the secondary windings similarly positioned as can be seen in Figure 6. Although not specifically shown, the rotor for this motor is of the conventional squirrel cage type. It is carried by the shaft 68 which is journaled in bearing members 80 mounted also in the mounting plate 72. The primary windings 76 of this motor are designed to be connected either in a series or parallel relationship and energized from a common source to create flux lines which flow in the core structure of the motor in such a manner that they normally do not thread the rotor element and therefore cause no rotation of the motor. Secondary windings 77 are similarly connected in either a series or parallel relationship and, as later noted, are designed to be connected to some type of controller which will short circuit or shunt the connections to the coils. With the primary windings 76 energized and secondary windings 77 open circuited, the flux lines created by the current flow in the primary windings 76 will circulate in a path through the yoke 73 (counterclockwise as seen in Figure 6) threading the windings 76, 77 and will not enter the poles 75a, 75b, 75c and 75d of the rotor, since the latter will provide a circuit of higher reluctance due to the air gap between the respective poles of the rotor. With the secondary 79 or control windings short circuited, the flux threading the secondary coils will cause a current to be generated therein which current will generate a counter flux to effectively saturate portions of the magnetic circuit of the motor and

force the main energizing flux lines from the primary coils 76 through the rotor element to cause a rotation of the motor rotor in a manner conventional with transformer motors. Under these conditions the flux paths for the flux lines created by the primary windings are through the portions of the yoke surrounded by the respective primary windings 76 in a counterclockwise direction, through the pole pieces 75a and 75c respectively, the rotor, the poles 75b and 75d respectively, and back through the portion of the yoke surrounded by the respective coils. The two flux paths so formed cause a clockwise rotating flux field and consequently clockwise rotation of the rotor or armature.

The primary 76 and secondary 77 coils of the motor are designed to be connected to a terminal block assembly 81 located in the upper end of casing member 12 and sealed therein. Terminal assembly 81 includes a terminal block 82 having a ridge or shoulder portion 83 thereon, the terminal block 82 extending into an aperture 84 in the upper end of casing 12 and abutting against a gasket 85 encircling said aperture in said casing through the shoulder 83. A flanged member 86 attached to casing member 12 by any suitable means, such as welding, is bent over the shoulder portion 83 of the terminal assembly to secure the terminal block 82 to the casing and provide a seal at this point through gasket 85. Included within the block 82 are four terminal posts 89 to which the extremities of the primary 76 and secondary 77 windings are connected. The upper surface of the terminal block is divided into four sections or compartments by means of a pair of transversely extending ridges or flanges 90, the terminal posts 89 terminating on the upper surface of the block in each of the compartments so formed. Primary windings 76 of the motor are connected through two of the posts 89 to a source of power by means of a cord 91 and plug 92, the wires from the cord being connected to the upper surfaces of the post by means of screws. These connections which lead to the power side (primary windings) of the motor are made at posts (also not shown) which are shorter than the posts connected to the secondary windings 77 in such a manner that a cover element 95 may be placed over the terminal block 82 to conceal such connections. The connections to the low voltage or secondary windings are made at the posts 89 which extend through the cover 95, as shown in Figure 2 and screws 93 which secure lead wires (not shown) are disposed outside of the cover such that connections to these posts may be made from outside the terminal assembly without necessitating a removal of the cover and exposure to the high voltage terminals. The cover 95 is secured to block 82 by means of a screw 97, the cover being made of an insulating material fitting tightly over the shoulder portions 83 of the block to seal this portion of the operator. Similarly the connection between the block 82 and casing 12 provides a seal at this point.

In operation, the operator is installed such that its output shaft 15 is extending downwardly and designed to move vertically into and out of the casing. This manner of installation insures an adequate level of oil at the pump. Primary windings 76 of the motor are energized through the cord 91 and plug 92 attached to a suitable source of power, this energization being continuous. Upon a need for operation of the operator, the low voltage windings 77 are short

circuited through a suitable controller (not shown) and the electric motor 70 commences rotation with the driving connection between cam 67 and ball linkage 66 imparting a reciprocating and oscillating motion to the piston 44 of pump 41. The oscillating movement of the piston member 44 operates to cover and uncover the inlet and outlet passages to the pump while reciprocating movement forces fluid through the pump and through the outlet passages 48 into the valve check mechanism 55 of the pump. Due to the pumping action, the fluid or working medium 40 is fed under pressure to the piston 56 and ball check member 62 of the check valve mechanism causing the return or outlet passage 58 to the sump to be closed and permitting flow of fluid through the ball or check valve mechanism through the passage 60 communicating with the variable chamber of the hydraulic actuator unit formed by the supporting plate 25 and diaphragm member 23. The fluid or working medium 40 under pressure urges the diaphragm 23 and hence the disk 21 and shaft 15 downwardly moving the shaft out of the confines of lower casing member 13 to cause the rotational movement of the pivoted output arm 16. Should the need for operation of the operator not be met or satisfied when the diaphragm and pivoted lever members reach their respective limits of movement, the electric motor 70 will stall under the build up in pressure load the pump and the unit will remain stalled until the secondary winding 71 of the motor are open circuited through the respective controlling device indicating the satisfaction of the need for operation of the operator. During this period should the pressure decrease on the pump side of the check valve mechanism, intermittent rotation of the motor and pumping action will take place to maintain the stalled pressure. Sufficient leakage past the piston of the piston member 44 pump is provided such that a decrease in pressure will be obtained on the pump side of the check valve whenever the motor is stopped. It will be understood that a small motor of this type would normally be a low torque device and consequently this leakage past the pistons of the pump also permits the motor to start rotating initially without being stalled by high pump pressure.

Upon the lack of need of operation of the operator, the electric motor is deenergized or stopped as indicated above and the leakage past the pump permits a drop in pressure on this side of the check valve. Piston 56 of the check valve member then moves under pressure from the actuator side of the pump to its inoperative position and the ball check member 62 returns to its closed position. Under such circumstances the outlet passage 58 is opened and a by-pass is formed between the variable chamber of the actuator and the sump through passages 60 and 58 to permit the flow of the working medium back into the oil reservoir or sump. The bias of the compression spring 22 urging disk 21 and diaphragm 23 to their inoperative positions moves this fluid under pressure back to the oil reservoir. At the same time the output lever or linkage 16 of the operator returns to its normal position.

In considering this invention it should be kept in mind that this disclosure is intended to be illustrative only and the scope of the invention is to be determined only by the appended claims.

I claim as my invention:

1. In a device of the class described, in combi-

nation, a first sealed chamber including an enclosing casing member and an end wall, a second casing member, means including said second casing member and said end wall forming a second chamber variable in volume and attached to said first sealed chamber, a pump mounted on said end wall and located within said first sealed chamber, said pump including a double ended reciprocating and oscillating piston member slidably positioned within a pair of cooperating cylinder members each having inlet and outlet passages leading thereto, the extremities of said piston member being notched to cooperate with said inlet and outlet passages upon oscillation and reciprocation of said piston member, said piston member having a diametrical dimension slightly less than the internal diametrical dimension of said cylinder members to provide for built in leakage past said pistons, a drive member mounted on said pistons intermediate its extremities, a small electric motor mounted on said pump and having limited starting torque at its output shaft for driving said pump, a coupling means connected to and driven by said output shaft of said motor and having a means eccentric of said shaft for connecting said drive member of said piston member to said coupling means to impart reciprocatory and oscillatory motion to said piston member as said motor is rotated, passage means connecting said inlet and outlet passages of said pump to said first and second chambers respectively, a third passage between said first and second chambers, means included in said third passage and controlled in one position by pressure of a fluid media which is pumped from said first to said second chamber upon operation of said motor and said pump for closing said third passage, the leakage of said pump permitting operation of the same upon initial energization of said motor and operation of said means in said third passage to open said passage upon stoppage of said motor and said pump.

2. In a device of the class described, in combination, a first sealed chamber including an enclosing casing member and an end wall, a second casing member, means including said second casing member and said end wall forming a second chamber variable in volume and attached to said first sealed chamber, a pump mounted on said end wall and located within said first sealed chamber, said pump including a double ended reciprocating and oscillating piston member slidably positioned within a pair of cooperating cylinder members each having inlet and outlet passages leading thereto, the extremities of said piston member being so formed that they are segmental in cross-section to thereby cooperate with the inlet and outlet passages of said cylinder upon oscillation and reciprocation of said piston member, said piston member and said cylinder so cooperating to provide for a predetermined amount of leakage past said piston member, a small electric motor mounted on said pump and having limited starting torque for driving said pump, an eccentric coupling means connecting said motor and said piston member and driven by said motor to impart reciprocatory and oscillatory movements to said piston member as said motor is rotated, means connecting said inlet and outlet passages of said pump to said first and second named chambers respectively, a third passage between said first and second chambers bypassing said pump, means included in said third passageway and controlled

in one position by pressure of a fluid medium which is pumped from said first to said second chambers upon operation of said motor and said pump for closing said third passageway, the leakage of said pump permitting operation of the same upon initial energization of the motor.

3. In a device of the class described, a first sealed chamber including an enclosing casing member and an end wall, a motorized pump within said chamber and mounted on said end wall, a second casing member, means including said second casing member and said end wall forming a second chamber variable in volume and attached to said first sealed chamber, a working medium within said first chamber, means including said pump having a built in leakage for moving said working medium from said first chamber to said second chamber upon the happening of a predetermined condition, means for moving said working medium from said second chamber to said first chamber in the absence of said predetermined condition, said second named means including valve means with a hollow piston member slidably positioned in a cooperating cylinder having inlet and outlet ports therein, a ball check valve positioned within said hollow piston member, said piston being movable within said cylinder upon the presence of a predetermined pressure at the pump to close said outlet port and permit passage of said working medium through said ball check valve and said inlet port into said variable chamber and to open said outlet port in the absence of said predetermined pressure at the pump, and means responsive to the presence of said working medium in said second chamber.

4. In a device of the class described, a first sealed chamber including an enclosing casing member and an end wall, a motorized pump within said sealed chamber and mounted on said end wall, a second sealed chamber formed by a flexible diaphragm and said end wall, a second casing member enclosing said second sealed chamber, one of said casing members including a shoulder portion which is bent over an edge of said end wall, an edge of said diaphragm and a shoulder portion on said other casing member to maintain said device in assembled relationship, and a beaded flange portion on the edge of said diaphragm abutting the peripheral side and end surfaces of the edge of said end wall and abutting both of said casing members to provide a seal for both said first and said second chambers.

5. In a device of the class described, a first sealed chamber including an enclosing casing member and an end wall, a motorized pump within said chamber and mounted on said end wall, a second sealed chamber formed by a flexible diaphragm and said end wall, a second casing member enclosing said second sealed chamber, means including said first and second casing members for maintaining said device in assembled relationship, a flange portion on said diaphragm abutting said casing members and said end wall to form a seal for said first and second chambers, a working medium within said first chamber, means including said pump having a built in leakage for moving said working medium from said first chamber to said second chamber upon the happening of a predetermined condition, means for moving said working medium from said second chamber to said first chamber in the absence of said predetermined condition, said second named means including

valve means with a hollow piston member slidably positioned in a cooperating cylinder having inlet and outlet ports therein, a ball check valve positioned within said hollow piston member, said piston being movable within said cylinder upon the presence of a predetermined pressure at the pump to close said outlet port and permit passage of said working medium through said ball check valve and said inlet port into said variable chamber and to open said outlet port in the absence of said predetermined pressure at the pump, and means responsive to the presence of said working medium in said second chamber.

6. In a device of the class described, in combination, a first sealed chamber including an enclosing casing member and an end wall, a second sealed chamber formed by a flexible diaphragm and said end wall, a second casing member enclosing said second sealed chamber, means including said first and second casing members for maintaining said device in assembled relationship, a flange portion on said diaphragm abutting said casing members and said end wall to form a seal between said first and second chambers, a pump mounted on said end wall and located within said first sealed chamber, said pump including a double ended reciprocating and oscillating piston member slidably positioned within a pair of cooperating cylinder members each having inlet and outlet passages leading thereto, the extremities of said piston member being notched to cooperate with said inlet and outlet passages upon oscillation and reciprocation of said piston member, said piston member having a diametrical dimension slightly less than the internal diametrical dimension of said cylinder members to provide for built in leakage past said pistons, a drive member mounted on said pistons intermediate its extremities, a small electric motor mounted on said pump and having limited starting torque at its output shaft for driving said pump, a coupling means connected to and driven by said output shaft of said motor and having a means eccentric of said shaft for connecting said drive member of said piston member to said coupling means to impart reciprocatory and oscillatory motion to said piston member as said motor is rotated, passage means connecting said inlet and outlet passages of said pump to said first and second chambers respectively, a third passage between said first and second chambers, means included in said third passage and controlled in one position by pressure of a fluid media which is pumped from said first to said second chamber upon operation of said motor and said pump for closing said third passage, the leakage of said pump permitting operation of the same upon initial energization of said motor and operation of said means in said third passage to open said passage upon stoppage of said motor and said pump.

7. In a device of the class described, in combination, a first sealed chamber including an enclosing casing member and an end wall, a second sealed chamber formed by a flexible diaphragm and said end wall, a second casing member enclosing said second sealed chamber, means including said first and second casing members for maintaining said device in assembled relationship, a flange portion on said diaphragm abutting said casing members and said end wall to form a seal between said first and second chambers, a pump mounted on said end wall and located within said first sealed chamber, said

pump including a double ended reciprocating and oscillating piston member slidably positioned within a pair of cooperating cylinder members each having inlet and outlet passages leading thereto, the extremities of said piston member being so formed that they are segmental in cross-section to thereby cooperate with the inlet and outlet passages of said cylinder upon oscillation and reciprocation of said piston member, said piston member and said cylinder so cooperating to provide for a predetermined amount of leakage past said piston member, a small electric motor mounted on said pump and having limited starting torque for driving said pump, an eccentric coupling means connecting said motor and said piston member and driven by said motor to impart reciprocatory and oscillatory movements to said piston member as said motor is rotated, means connecting said inlet and outlet passages of said pump to said first and second named chambers respectively, a third passage between said first and second chambers bypassing said pump, means included in said third passageway and controlled in one position by pressure of a fluid medium which is pumped from said first to said second chambers upon operation of said motor and said pump for closing said third passageway, the leakage of said pump permitting operation of the same upon initial energization of the motor.

8. In a device of the class described, in combination, a first sealed chamber including an enclosing casing member and an end wall, a second sealed chamber formed by a flexible diaphragm and said end wall, a second casing member enclosing said second sealed chamber, means including said first and second casing members for maintaining said device in assembled relationship, means including said first and second casing members and a peripheral edge of said diaphragm for maintaining said device in assembled relationship and sealing said second chamber, a pump mounted on said end wall and located within said first sealed chamber, said pump including a double ended reciprocating and oscillating piston member slidably positioned within a pair of cooperating cylinder members each having inlet and outlet passages leading thereto, the extremities of said piston member being notched to cooperate with said inlet and outlet passages upon oscillation and reciprocation of said piston member, said piston member having a diametrical dimension slightly less than the internal diametrical dimension of said cylinder members to provide for built in leakage past said pistons, a drive member mounted on said pistons intermediate its extremities, a small electric motor mounted on said pump and having limited starting torque at its output shaft for driving said pump, a coupling means connected to and driven by said output shaft of said motor and having a means eccentric of said shaft for connecting said drive member of said piston member to said coupling means to impart reciprocatory and oscillatory motion to said piston member as said motor is rotated, passage means connecting said inlet and outlet passages of said pump to said first and second chambers respectively, a third passage between said first and second chambers, means included in said third passage and controlled in one position by pressure of a fluid media which is pumped from said first to said second chamber upon operation of said motor and said pump for closing said third passage, the leakage of said pump permitting

operation of the same upon initial energization of said motor and operation of said means in said third passage to open said passage upon stoppage of said motor and said pump.

- 5 9. In a device of the class described, in combination, a first sealed chamber including an enclosing casing member and an end wall, a second sealed chamber formed by a flexible diaphragm and said end wall, a second casing member enclosing said second sealed chamber, means including said first and second casing members for maintaining said device in assembled relationship, means including said first and second casing members and a peripheral edge of said diaphragm for maintaining said device in assembled relationship and sealing said second chamber, a pump mounted on said end wall and located within said first sealed chamber, said pump including a double ended reciprocating and oscillating piston member slidably positioned within a pair of cooperating cylinder members each having inlet and outlet passages leading thereto, the extremities of said piston member being so formed that they are segmental in cross-section to thereby cooperate with the inlet and outlet passages of said cylinder upon oscillation and reciprocation of said piston member, said piston member and said cylinder so cooperating to provide for a predetermined amount of leakage past said piston member, a small electric motor mounted on said pump and having limited starting torque for driving said pump, an eccentric coupling means connecting said motor and said piston member and driven by said motor to impart reciprocatory and oscillatory movements to said piston member as said motor is rotated, means connecting said inlet and outlet passages of said pump to said first and second named chambers respectively, a third passage between said first and second chambers bypassing said pump, means included in said third passageway and controlled in one position by pressure of a fluid medium which is pumped from said first to said second chambers upon operation of said motor and said pump for closing said third passageway, the leakage of said pump permitting operation of the same upon initial energization of the motor.
- 10 10. In a device of the class described, a first sealed chamber including an enclosing casing member and an end wall, a motorized pump within said chamber and mounted on said end wall, a second sealed chamber formed by a flexible diaphragm and said end wall, a second casing member enclosing said second sealed chamber, means including said first and second casing members for maintaining said device in assembled relationship, means including said first and second casing members and a peripheral edge of said diaphragm for maintaining said device in assembled relationship and sealing said second chamber, a working medium within said first chamber, means including said pump having a built in leakage for moving said working medium from said first chamber to said second chamber upon the happening of a predetermined condition, means for moving said working medium from said second chamber to said first chamber in the absence of said predetermined condition, said second named means including valve means with a hollow piston member slidably positioned in a cooperating cylinder having inlet and outlet ports therein, a ball check valve positioned within said hollow piston member, said piston being movable within said cylinder upon the presence

13

of a predetermined pressure at the pump to close said outlet port and permit passage of said working medium through said ball check valve and said inlet port into said variable chamber and to open said outlet port in the absence of said predetermined pressure at the pump, and means responsive to the presence of said working medium in said second chamber.

CARL J. BISHOFBERGER.
